CLAIM

The ornamental design for a TV receiver, as shown and described.

DESCRIPTION

- 1. TV receiver
- 1.1 : Perspective
- 1.2 : Rear perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Enlarged

The evenly-spaced broken lines in the figures, including the broken lines showing the panels, vent and circular button feature on the back of the TV receiver and flat and protruding rectangular features on bottom of TV receiver are for the purpose of illustrating portions of the article and form no part of the claimed design. The dot-dash broken lines shown in FIGS. 1.9-1.11 are for the purpose of illustrating partially enlarged views only and form no part of the claimed design.

1 Claim, 10 Drawing Sheets
